UNITED STATES PATENT OFFICE
CERTIFICATE OF CORRECTION

Design No. 181,923

January 21, 1958

Roy A. Cramer

It is hereby certified that error appears in the above numbered patent requiring correction and that the said Letters Patent should read as corrected below.

In the grant, lines 1, 2, and 3, for "Roy A. Cramer, of Kansas City, Missouri" read -- Roy A. Cramer, of Kansas City, Missouri, assignor to Cramer Posture Chair Company, Inc., of Kansas City, Missouri, a corporation of Missouri; line 13, for "Roy A. Cramer, his heirs" read -- Cramer Posture Chair Company, Inc., its successors --; in the heading to the drawings and printed specification, line 3, for "Roy A. Cramer, Kansas City, Mo." read -- Roy A. Cramer, Kansas City, Mo., assignor to Cramer Posture Chair Company, Inc., Kansas City, Mo., a corporation of Missouri --.

Signed and sealed this 11th day of March 1958.

(SEAL)
